UNITED STATES PATENT OFFICE.

FRANK J. NOVAK AND FRANK J. CISEK, OF SCAPPOOSE, OREGON.

CAR-DOOR-SECURING MEANS.

Application filed July 14, 1925. Serial No. 43,643.

This invention relates to car doors, and more particularly to means for securing car doors in closed position.

The invention has for one of its objects 5 the provision of novel, simple and inexpensive means through the medium of which the car door forming the subject matter of our U. S. Letters Patent No. 1,489,959, granted April 8, 1924, and other similar doors, can 10 be secured in closed position with the outer sides of their lateral edge portions in full abutting contact with the inner surfaces of the sides of the car.

The foregoing and other objects are attained by the construction, combination and arrangement of parts hereinafter fully described and claimed, and illustrated in the accompanying drawings, wherein:

Figure 1 is a sectional view taken on a 20 plane extending vertically and centrally through a fragmentary portion of a box car equipped with door securing means embodying our invention;

Figure 2 is a sectional view taken on the 25 vertical plane indicated by the line 2—2 of Figure 1;

Figure 3 is a sectional view taken on the horizontal plane indicated by the line 3—3 of Figure 1;

Figure 4 is a sectional view taken on the 30 vertical plane indicated by the line 4—4 of Figure 1, and

Figure 5 is a sectional view taken on the horizontal plane indicated by the line 5—5 35 of Figure 1.

Corresponding and like parts are referred to in the following description, and designated in the several views of the accompanying drawings by similar reference characters.

In the drawings 1 designates the side of a box car which is provided with the usual door opening 2. A door 3 for closing the opening 2 is slidably suspended from a track 4 by hangers 5. The door 3 is provided with an opening which is adapted to be closed by a plate 7 which is slidably supported on the door by a guide 8. A rod 9 is slidably mounted in brackets 10 secured to 45 the door 3, and has its lower end connected to the plate 7. A hand wheel 11 having threaded engagement with the rod 9 and resting upon the upper bracket 10 provides means by which the plate 7 may be raised 50 to uncover the opening 6 and lowered to close said opening. A strip 12 secured to

the lower edge of the door 3 rests in the groove of a track 13 secured to the floor of the car.

Casings 14 are secured to the side 1 of the car adjacent the door posts 2^a. The casings 14 are fully open at their inner sides, and the bottom walls 15 thereof are inclined downwardly and inwardly to prevent foreign matter from accumulating within the casings. Bolts 16 which pass through the side 1 secure the casings 14 in place, and they are provided at their outer ends with nuts 17 and at their inner ends with heads 18. Metal strips 19 are positioned between the outer surface of the side 1 and the nuts 17 to prevent the strain on the bolts 16 from pulling the nuts 17 into the side 1. Lock bolts 20 are pivoted to the heads 18 by pins 21. Nuts 22 provided with actuating levers 22^a are carried by the bolts 20. The free ends of the bolts 20 are flanged over as at 23 to prevent the loss of the nuts 22. Keepers 24 are secured to the door 3 and are provided with slots 25 for the reception of the bolts 20. To permit the bolts 20 to be engaged with and disengaged from the keepers 24, the slots 25 are open at their lower ends. When the bolts 20 are engaged with the keepers 24 and the nuts 22 turned up 55 into contact with the keepers, the door 3 is firmly secured in closed position. When it is desired to open the door 3, it is only necessary to turn back the nuts 22 and swing the bolts 20 into the casings 14. A stop 26 is 60 adapted to limit the closing movement of the door and a stop 27 is adapted to limit the opening movement thereof, and the door is provided with handles 28 to permit of its being readily moved into opened or closed 65 position. When the door reaches its closed position as determined by the stop 26, the slots 25 are in position to permit the bolts 20 to be swung into engagement with the keepers 24. When the door 3 reaches 70 opened position as determined by the stop 27, two of the keepers 24 will be positioned for engagement by two of the bolts 20.

From the foregoing description, taken in connection with the accompanying drawings, it should be apparent that the securing means is adapted to hold the door 3 in either closed or opened position and that it will not interfere with the movement of the door from closed to opened or from opened to 75 closed position. It will also be apparent that the securing means is strong, durable and ef- 80

ficient, and that it may be readily secured to a car.

While we have described the principle of operation of the invention, together with the device which we now consider to be the best embodiment thereof, we desire to have it understood that the device shown is merely illustrative, and that such changes may be made when desired as are within the scope of the invention as claimed.

What is claimed is:

1. Car door securing means comprising a slotted keeper secured to the door, a retaining bolt secured to the car, a housing secured to the car by the retaining bolt and having an open side, a keeper-engaging bolt pivoted to the retaining bolt and located wholly within the housing when out of engagement with the keeper and adapted to be swung through the open side of the hous-

ing into engagement with the keeper, and a keeper-contacting nut carried by the keeper-engaging bolt.

2. In combination, a car having an opening, a door for the opening, means supporting the door for horizontal sliding movement into opened and closed positions, keeper plates secured to the door and projecting beyond the vertical edges thereof, bolts pivoted to the car adjacent the vertical walls of the opening thereof and adapted to be engaged with the keeper plates when the door is closed, certain of said bolts being adapted to be engaged with certain of said keeper blades when the door is opened, and keeper-contacting nuts carried by the bolts.

In testimony whereof we affix our signatures.

FRANK J. NOVAK.
FRANK J. CISEK.
